UNITED STATES PATENT OFFICE.

WILLIAM JACKSON, OF ALLEGHENY, ASSIGNOR TO THE PITTSBURGH TUBULAR STEEL WHIFFLETREE COMPANY, OF PITTSBURG, PENNSYLVANIA.

MACHINE FOR APPLYING FITTINGS AND TRIMMINGS ON TUBULAR ARTICLES.

SPECIFICATION forming part of Letters Patent No. 425,510, dated April 15, 1890.

Application filed August 8, 1889. Serial No. 320,183. (No model.)

To all whom it may concern:

Be it known that I, WILLIAM JACKSON, a resident of Allegheny, in the county of Allegheny and State of Pennsylvania, have invented a new and useful Improvement in Machines for Applying Fittings and Trimmings on Tubular Articles; and I do hereby declare the following to be a full, clear, and exact description thereof.

10 My invention relates to machines for applying fittings or trimmings—such as the collars, hooks, &c.—to whiffletrees or like tubular articles—such as axles or axle-skeins—its object being to provide a machine by which 15 the labor heretofore incident in applying the trimmings to these articles can be practically overcome and the work performed with rapidity.

In applying fittings to tubular metal whiffletrees such as have heretofore been formed it has been customary to heat the trimmings so as to expand them, and then by means of sledges drive the tubular metal blank through or into the trimming or the 25 fitting onto the blank. This operation was slow and required heavy manual labor, and beside this there was great liability of spoiling the blanks either by the blows of the sledge on the end of the blank so swaging it 30 out of shape, or where the fittings were a rather tight fit and it was found impossible to drive them to place before the fittings cooled and contracted, so spoiling both blank and fitting. The placing of these fittings on 35 these peculiar blanks has been one of the serious items of cost in the manufacture of these articles, materially increasing their cost upon the market.

By my invention I am enabled to apply 40 these fittings to the whiffletrees or other such tubular articles and with practically no manual labor and to insure their rapid and accurate adjustment on the blanks.

To these ends my invention comprises, generally stated, a reciprocating press, stationary shoulder or face to hold the fitting against longitudinal movement, and a longitudinally-moving holder to fit within and support the fitting, so that the blank may be forced into 45 the fitting, the holder being pressed back by the blank and permitting it to enter the same.

It also comprises a support provided with two die plates or faces, each having a recess therein, so that these die-plates fit around the body of the blank and hold the fitting 55 against longitudinal movement, while the press forces the blank into the same.

It also comprises certain other improvements, all of which will be more fully herein-after set forth.

To enable others skilled in the art to make and use my invention, I will describe the same more fully, referring to the accompanying drawings, in which—

Figure 1 is a top or plan view of said apparatus, showing the same with the fittings and blank in position for applying the fittings thereto. Fig. 2 is a like view showing the trimmings applied to the blank. Fig. 3 is a longitudinal central section of the operative 65 parts of the machine. Fig. 4 is a cross-section on the line 3 3, Fig. 1. Fig. 5 is a cross-section on the line 5 5, Fig. 3. Fig. 6 is a cross-section on the line 6 6, Fig. 3, looking in the opposite direction. Fig. 7 is a longitudinal view on the line 7 7, Fig. 6. Fig. 8 is a perspective view of the removable holder for the central fitting. Fig. 9 is a like view of the longitudinally-moving holder for the 70 end fitting, and Fig. 10 is a back view of the 75 holder for the end fitting suitable for applying an oval-shaped fitting.

Like letters and figure of reference indicate like parts in each.

The machine is supported on a suitable bed 85 having at one end thereof the engine-cylinder A and at the other end the abutment B and connecting the same the cylindrical side bars C C, these side bars forming a strong connection between the cylinder and the end abutment and enabling the machine to sustain exceedingly heavy pressure. Working in the cylinder is the suitable piston, the piston-rod d of which I connect to the reciprocating press D, which slides upon the side bars C C, the 90 movement of said reciprocating press D being controlled by the valve a through the valve-lever a', the valve being of any suitable construction. The machine has also the stationary cross-head E, which is supported upon 95 the side bars C C by suitable sleeves e, these sleeves being so arranged as to be clamped 100

upon the side bars and hold the head E in any position to which it is adjusted, according to the length of the blank, and back of that head suitable collars E' being placed, 5 which engage with the side bars C C by means of set-screws and so enable the head to sustain the heavy strain brought upon it. Between the reciprocating head D and stationary head E is the central cross-head or support F, 10 which is clamped to the side bars C C by sleeves f' and braced by collars F' in the same way as was described in connection with the head E. The head E and central head F may be adjusted upon the side bars to the proper 15 position, according to the length of the whiffle-tree or other like article to which the fittings are to be applied, and fixed firmly in these positions by clamping upon the side bars and by means of their bracing-collars, so that during 20 the operation of the machine these cross-heads are held stationary.

For placing the end fittings in the whiffle-tree, to which class of articles the description given will most particularly refer, I employ 25 in the pressing-head D and the end cross-head E suitable holders for the end fittings, the construction of these holders being substantially the same in each case, so that the description of the one will suit for each. In 30 the body of the cross-head is formed a recess g', Fig. 3, into which the sleeve g fits, said sleeve having a flange g² fitting against the face of the cross-head and having therein an annular recess g³, into which a screw-bolt g⁴, 35 passing through the body of the cross-head, engages with the sleeve g. Within the cross-head beyond the recess g' is a recess h', and fitting within the sleeve g and said recess h' is the longitudinally-moving holder h for the fitting l, this holder having the extension h², 40 around which the spring i fits, the backward movement of the holder being sustained by the stop-bolt i', extending down into the recess h', and against which bolt the extension h² strikes when the holder is pressed back to 45 its farthest position. The holder h has also the flange h³, which strikes against the shoulder g⁵ in the sleeve g and so limits the forward movement of the holder. The forward end of the 50 holder is formed of shape and size corresponding to the interior of the fitting and to the end of the blank to be forced into the fitting, the holder being cylindrical where the end of the blank is cylindrical, as is shown 55 in Fig. 9, and the forward end h⁴ being formed oval, as shown in Fig. 10, where the end of the blank is oval and an oval fitting is employed. At the end of the holder is the front face k, Fig. 10, which forms a shoulder against 60 which the end of the blank presses, so that the blank will by pressing on the longitudinally-moving holder force it back, following it through the fitting supported on the holder and occupying the space therein previously 65 occupied by the holder. Beyond this front face k is the guiding-point k', which directs the end of the blank against the front face k

and into proper position to enter the fitting, as clearly shown in Fig. 3.

The central cross-head F, when employed 70 for applying the cylindrical fitting 2 to the whiffle-tree, has certain essentials, such as that it shall permit the travel of the whiffle-tree-blank through it while sustaining the central fitting 2 against longitudinal movement, and 75 that it must be of sufficient strength to sustain very heavy strain in forcing the fitting or collar clear to the proper position, while after the collar has been brought to that position the part sustaining the pressure of the 80 collar must be opened so as to permit of the withdrawal of the blank after the placing of the fittings thereon, since the fitting applied to the end of the blank is larger than the central body of the blank and would prevent 85 the withdrawal of the blank through the cross-head. In providing for this I form the body f' at the cross-head with a depression f², Fig. 3, permitting the passage of the blank through the same, and a recess f³ to receive 90 the fitting-holder 1, into which the central fitting 2 is placed, and by which it is held in proper position to be placed upon the blank. Above the cross-head F is the upper die-holder M, which is vertically movable and is 95 raised by the perpendicular bar m, Figs. 4 and 6, extending through the cross-head, which bar is engaged by the lever m' pivoted at r.v² and operated by the treadle m³, said lever having the weight m⁴ therein to counterbalance the weight of the upper die-holder, which is made exceedingly heavy and strong to sustain the strain. The shape of this upper die-holder is fully shown in longitudinal section in Fig. 6 and in cross-section in Fig. 105 7, it having a recess n to permit the passage of the body of the blank and having a series of tongues n' fitting into grooves in the cross-head F, said cross-head having like tongues n² fitting into grooves in the upper die-holder, 110 and several of the interlocking tongues and grooves being employed so as to form an exceedingly strong connection between the upper die-holder and cylinder cross-head at the point at which strain is brought upon the 115 same.

Fitting in grooves p' in the cross-head F is the lower die-plate p, the grooves p' being formed between the depression f² and the recess f³ and so holding the lower die-plate p 120 in proper position, this lower die-plate having formed therein the recess p², corresponding to the shape of one-half of the body of the whiffle-tree at the point where the cylindrical fitting is placed thereon. Secured to 125 the upper die-holder M is the upper die-plate r, which fits in a seat in said die-holder, and is held therein by a screw-bolt r', the lower edges of the die-plate descending into the grooves p', and so being braced or supported both by 130 the upper die-holder and the cross-head F. In the upper die-plate r is formed the recess r², corresponding to one-half of the body of the blank, as before stated, as to the recess

p^2 , and these recesses $p^2 r^2$ permitting the passage of the body of the blank through the die formed by the two die-plates, but the edges of the recesses fitting closely around the blank and sustaining the fitting 2 from longitudinal movement, so providing for forcing the fitting to the proper place upon the blank as the blank is forced by the press D through the die. The fitting-holder 1 is a hollow block which corresponds in width to the width of the recess f^3 in the cross-head and rests in said recess, though the blocks l may be made of different lengths, according to the length of the fitting to be supported thereby. It has the seat l' therein corresponding in length and width to the length and transverse diameter of fitting, and has at or near the center of the side walls the grooves l^2 , Fig. 3, in which the loop or ring 3 of the fitting can enter and by which the fitting is held in proper position, so that the loop or ring on the central fitting and the loops or hooks 4 on the end fittings are in proper relative position to each other. At the forward end of the recess f^2 of the cross-head F are the guide-plates s, these guide-plates being bolted to the cross-head, as at s', and passing downwardly on each side of the space through which the blank should pass, as is fully shown in Fig. 4, and so holding the blank in proper line relative to the opening in the die-plates and the fitting-holders in the cross-head E and pressing-head D, these guide-plates s being adjustable, according to the different sizes of plates to be trimmed.

When the apparatus is in use, the fitting-holders h h extend out beyond the sleeves g g in the press D and cross-head E, and the operator places upon these fitting-holders the end fittings l l and drops into the central fitting-holder 1 the central fitting 2, these fittings being generally heated so as to expand the same and provide for their shrinking upon the blank when placed thereon. He then takes the tubular whiffletree-blank which has been tapered from the central portion toward the ends, and which is preferably flattened so as to impart to the central part of its body an oval shape in cross-section, and he passes it through the central fitting, the one end of the blank passing through the die-plates in the central cross-head, and then after the other operator admits steam to the proper side of the cylinder to force the pressing-head D forward he guides the opposite end of the blank so as to cause it to engage with the guiding-point k' of the fitting-holder h in the press D. A strong pressure is then imparted to the pressing-head D, and it forces the blank through the cylindrical fitting, so that the other end of the blank engages with the fitting-holder h in the cross-head E. As the pressure is continued, the two end fitting-holders h h are forced by the ends of the blank into their respective heads, the ends of the blank passing within the fittings supported by said fitting-holders,

so applying the end fittings to the blank. At the same time the cylindrical fitting presses against the die-plates p r, its holder 1 moving with it, and the blank is forced through said die-plates, the cylindrical fitting is forced along said blank until brought to the proper position thereon, the one operation thus applying both the central fitting and the end fittings to the blank. As soon as this is accomplished the operator through the treadle m³ raises the upper die-holder M, and with it the upper die-plate r, and as soon as the pressing-head D is drawn back the blank can be removed from the apparatus and the operation repeated. The fittings can thus be quickly applied to the blank, and as they cool they will shrink firmly upon the same, so forming an extremely strong connection between the fittings and the blank. Indeed, in some cases it is not found necessary to heat the fittings, as the power generated is sufficient to force the blanks in position even when cold. All the fittings can thus be applied to the blank at one operation and without the necessity of staving up one end of the blank in driving it into the other fitting, which frequently occurred and required the retapering of the end of the blank to bring it of the proper shape, and all heavy manual labor is overcome.

The sleeves g, with the fitting-holders h moving therein, die-plates p r, and the central fitting-holder 1 can be easily and quickly changed, so that the machine is capable of applying different sizes of fittings, according to the size of blank to be trimmed. The cross-heads E and F can also be moved upon the said bars C C, according to the different lengths of blanks to be trimmed. In case the ends of the blank are oval the fittings may be applied thereto in the way above described by the employment of holders therefor, such as shown in Fig. 10, the ends h⁴ of the holders being formed corresponding to the interior shape of the fittings, and in order to hold them in proper line, the holders having a key-way t formed therein engaging with a key in the sleeve g, the sleeves g may be held in proper position in their respective heads by means of the bolts g².

I am thus enabled by my invention to do away with the extremely heavy manual labor heretofore found in applying these fittings to the blanks, reducing the number of workmen required for the purpose, and at the same time the apparatus is capable of trimming many times the number of blanks in the same period.

The apparatus may also be employed for the trimming of other articles—such as axles or axle-skeins—having many advantages for that purpose.

What I claim as my invention, and desire to secure by Letters Patent, is—

1. In machines for applying fittings to tubular and other blanks, the combination of a pressing-head, a stationary shoulder or face to hold the trimming from longitudinal move-

- ment, and a longitudinally-moving holder fitting within and supporting the fitting, whereby the blank may be forced into the fitting, the holder being pressed back by the blank, substantially as and for the purposes set forth. 5
2. In machines for applying fittings to tubular and other blanks, the combination of a pressing-head, a stationary supporting-head, and longitudinally-movable holders in said heads fitting within and supporting the fittings, whereby both ends of the blank may be forced into the fittings supported on the holders at the same time, substantially as and for the purposes set forth. 10
- 15 3. In machines for applying fittings to tubular and other blanks, the combination of a pressing-head and a stationary support having a partible die therein provided with a recess corresponding to the body of the blank, whereby the blanks may be forced through the die while the fitting is held thereby, substantially as and for the purposes set forth. 20
4. In machines for applying fittings to tubular and other blanks, the combination of the pressing-head having a longitudinally-movable holder therein, and a stationary head having a die therein provided with a recess corresponding to the body of the blank, whereby the blank may be forced through the die, 25 the central fitting brought to place thereon, and the end of the blank forced into the fitting, substantially as and for the purposes set forth. 30
5. In machines for applying fittings to tubular and other blanks, the combination of the stationary head having a fittings-holder therein, cross-head having two die-plates therein provided with recesses corresponding to the body of the blank, said die-plates being partible, and a pressing-head, substantially as and for the purposes set forth. 35
- 40 6. In machines for applying trimmings to tubular and other blanks, the combination of a cross-head having a die therein provided with a recess corresponding to the body of the blank, a support or holder for the fitting supported in front of said die, and a pressing-head whereby the blank may be forced through the fitting supported on said holder 45 and through the die in said cross-head, substantially as and for the purposes set forth. 50
- 55 7. In machines for applying fittings to tubular and other blanks, a longitudinally-moving fitting-holder corresponding in shape to the interior of the fitting, and having a face thereon against which the blank may press so as to force the holder out of the fitting when it enters therein, substantially as and for the purposes set forth. 60
- 65 8. In machines for applying fittings to tubular and other blanks, a longitudinally-movable fitting-holder corresponding in shape to the interior of the fitting and having a guide-point at the end thereof, and a face around said guide-point against which the blank may
- press in forcing the holder out of the fitting, substantially as and for the purposes set forth. 70
9. In machines for applying fittings to tubular and other blanks, the combination of the cross-head, the sleeve *g*, fitting therein, the fitting-holder *h*, moving longitudinally within said sleeve and having the flange *h*³, and the spring *i*, confined within said cross-head, substantially as and for the purposes set forth. 75
10. In machines for applying fittings to tubular and other blanks, the combination of the cross-head, the sleeve *g*, fitting therein, and the fitting-holder *h*, having a keyway *t* engaging with the key in said sleeve, substantially as and for the purposes set forth. 80
11. In machines for applying fittings to tubular and other blanks, the combination of a cross-head *F*, carrying the lower die-plate *p*, and the movable upper die-holder *M*, carrying the upper die *r*, said dies *p* and *r* having recesses therein for the passage of the body of the blank, substantially as and for the purposes set forth. 85
12. In machines for applying fittings to tubular and other blanks, the cross-head *F*, in combination with the upper die-holder *M*, said cross-head and holder having the interlocking tongues *n*¹ *n*², substantially as and for the purposes set forth. 90
13. In machines for applying fittings to tubular and other blanks, the cross-head *F*, having grooves *p*', in combination with the lower die-blank *p*, and the upper die-holder *M*, having the upper die-plate *r*, the lower ends of which fit in said grooves, substantially as and for the purposes set forth. 95
14. In machines for applying fittings to tubular and other blanks, the combination of the cross-head *F*, the upper die-holder *M*, the sliding bar *m*, engaging therewith and passing through the cross-head, and the lever *m'* for operating said upper die-holder, substantially as and for the purposes set forth. 105
15. In machines for applying fittings to tubular and other blanks, the central fitting-holder *l*, having the seats *l'* to receive the body of the fitting, and the grooves *l*² in its side walls, substantially as and for the purposes set forth. 110
16. In machines for applying fittings to blanks, the combination of the machine-frame having the side bars *C*, the pressing-head *D*, moving thereon, the cross-heads *EF*, longitudinally adjustable upon said side bars, and sleeves or collars for clamping the same firmly to said side bars, substantially as and for the purposes set forth. 115

In testimony whereof I, the said WILLIAM JACKSON, have hereunto set my hand.

WILLIAM JACKSON.
